LIQUID FILLING MACHINE

Clinton Kraus, Keansburg, and Victor C. Luff,
Elizabeth, N. J., assignors to American Can
Company, New York, N. Y., a corporation of
New Jersey

Application May 9, 1936, Serial No. 78,916

4 Claims. (Cl. 226—97)

The present invention relates broadly to the filling of containers with measured quantities of liquid and has particular reference to piston and cylinder measuring elements for liquid filling machines by means of which more accurate measuring of the liquid charges is obtained with the minimum of and the simplicity in the moving parts to effect such measuring.

The present invention contemplates the association, in a liquid filling machine, of high speed can feeding and handling devices and accurate quick acting piston and valve mechanism which cooperate in definite time relation to provide for the successive presentation of cans to be filled and for uniform and accurate filling of the cans with measured liquid charges and for subsequent release or removal of the filled cans from the machine, all of the operations being automatic and providing for quick and accurate filling without 20 spilling.

The invention also contemplates, as an added feature in such apparatus, the removal by suction of any extraneous drops or drips of liquid from the filling elements.

An object of the invention is the provision of a liquid filling apparatus for automatically and accurately conditioning a can to be filled while advancing it through a filling cycle in which an accurate measured quantity of liquid is dispensed from a measuring chamber, such filling however taking place only in the event that there is a can in proper position to be filled, the filling cycle also including blocking off of any further flow of extraneous or surplus liquid and thus preventing dripping of the liquid from the filling elements.

A further object of the invention is the provision of an apparatus of the character described which utilizes a series of filling units, each unit including a measuring cylinder and discharge piston and all of these units are so timed in their operations as to allow for a number of cans in different stages of filling, this arrangement permitting an unrestricted successive entrance of 45 empty cans into the machine and an unrestricted flow of filled cans therefrom.

Another object of the invention is the provision of can holding fingers in such a filling machine which are adapted to hold in proper accurate filling position even a tall small diameter can and a can fairly light in weight as for example a fibre body can which may also have relatively fragile or resilient walls which require special care in handling.

Yet another object is the provision in such a

liquid filling machine of a measuring chamber and piston construction in which the supplying of each chamber with liquid effects the moving of its piston and through such movement the measurement and discharge of the liquid from one end of the chamber, other liquid at the same time passing into another part of the chamber so that the chamber is never empty notwithstanding the repeated measurement and discharge of liquid going into the cans being filled.

Still another object of the invention is the provision of a filling machine having a reservoir and a plurality of measuring chambers, each chamber being associated with a movable valve member which functions to provide for or cut off the flow of liquid from the reservoir to the chamber, the valve members also controlling the flow of liquid from the measuring chambers into the cans.

Numerous other objects and advantages of the invention will be apparent as it is better understood from the following description, which, taken in connection with the accompanying drawings, discloses a preferred embodiment thereof.

Referring to the drawings:

Figure 1 is a plan view of a can filling apparatus embodying the present invention, parts being broken away;

Fig. 2 is a longitudinal sectional view of one side of the filling apparatus, this being substantially a vertical section taken along the line 2—2 in Fig. 1;

Fig. 3 is a plan sectional view taken substantially along the line 3—3 in Fig. 2 and illustrating the passage of cans through the machine, parts being broken away;

Fig. 4 is a sectional detail of the can feed-in device as viewed substantially along the line 4—4 in Fig. 3;

Fig. 5 is a fragmentary plan view of a part of the can feed-in device and associated can receiving parts of the apparatus, this view illustrating a different position of cans from that disclosed in Fig. 3;

Fig. 6 is a sectional view taken substantially along the line 6—6 in Fig. 3 and illustrating the entrance into and the discharge from the apparatus, respectively, of empty and filled cans and also showing parts of a no-can-no-fill device;

Fig. 7 is a plan sectional detail taken substantially along the line 7—7 in Fig. 6;

Fig. 8 is a fragmentary elevation of one of the filling units of the machine as viewed from a posi-

tion graphically indicated by the circular dot-and-dash line 8—8 in Fig. 1;

Figs. 9 and 10 are similar views of the lower part of the mechanism disclosed in Fig. 8 showing different positions of the movable elements;

Fig. 11 is a fragmentary sectional view taken substantially along the broken line 11—11 in Fig. 1 and illustrating the filling of a can with liquid;

Figs. 12 and 13 are sectional plan and transverse sectional views of the mechanism illustrated in the upper part of Fig. 11, Fig. 12 being taken substantially along the line 12—12 in that figure and Fig. 13 being taken substantially along the broken line 13—13 in Fig. 12;

Fig. 14 is a sectional view of the discharge valve chamber this being drawn to slightly larger scale but showing some of the same parts as are shown to the right of Fig. 11;

Fig. 15 is a sectional detail taken substantially along the line 15—15 of Fig. 14; and

Figs. 16 to 21, inclusive, are sectional details of one of the valve mechanisms showing its relation to an associated measuring chamber, the different views showing different valve positions, Figs. 16, 17, 18 and 19 being taken substantially along the respective section lines 16—16, 17—17, 18—18 and 19—19 in Fig. 2 but drawn to a larger scale, Fig. 20 being the same section as Fig. 18 but showing a different position of valve parts and Fig. 21 illustrating the same parts as shown in Fig. 19 but in a different position.

The apparatus embodying the present invention comprises a stationary platform onto which cans are advanced for filling and over which the cans are moved in a circular path of travel. It during this travel that each can receives its measured charge of liquid. Relatively tall and small diameter cans *a* are selected by way of illustration in the drawings as such a shape of can is more difficult to feed and fill, this type of can being formed with a fibre body wall and a metal bottom. Such a can is also light in weight and for this reason is more subject to tipping or getting out of alignment. The special provisions for holding the can in proper position at all times are a feature of the instant apparatus as will be hereinafter fully discussed.

The cans *a* are brought into the machine on a conveyor unit broadly designated by the letter *b* and as best illustrated in Figs. 1 and 3 the cans move in processional order into the filling machine. From the conveyor unit, the cans pass onto a stationary platform or table of the machine proper, this platform being broadly indicated by the letter *c*. The cans are moved along this platform during the filling operation.

The walls of the fibre can *a* are more or less flexible and provision is made to prevent denting the body wall which includes accurately timing entrance of the cans into the pockets of a revolving turret member *d* which propels the cans over the stationary platform *c*. In the timing action the entire row of cans on the conveyor *b* is momentarily held back until the turret pocket is in proper can receiving position, the timing device being broadly designated by the letter *e* (Figs. 3, 4, 5 and 6).

Just after a can has been deposited in the revolving turret member *d* it actuates a can trip device best illustrated in Figs. 2 and 3 and designated broadly by the letter *f*. The can trip device operates as a no-can-no-fill unit and this insures that the necessary setting be made for certain machine parts associated with the filling of the can.

The turret member *d* supports a central storage reservoir *g* in which the liquid for filling the cans is forced under pressure. The fibre can under consideration is well adapted to hold lubricating oil and when filling such oil cans, this oil would constitute the liquid forced under pressure into the reservoir. A series of measuring chambers *h* are disposed concentrically with and are arranged above and extend beyond the outer edge of the turret member. The filling head and chambers move with and are carried by the turret member and when a can has been located within a pocket of the turret it is in correct filling position relative to its associated measuring chamber.

A head valve *j* is a part of each filling head unit and is associated with each measuring chamber. In one position the valve permits communication between the reservoir *g* and one end of the corresponding measuring chamber *h*. In another position the opposite end of the chamber connects with the reservoir and there are positions when all communications are cut off. Figs. 16 to 21, inclusive, illustrate in detail these various positions of the head valve and these will be referred to in proper sequence in the description which follows. Each head valve *j* is controlled by valve actuating instrumentalities *k* (Figs. 2, 8, 9 and 19) which in turn operate in accordance with certain settings of the can trip device *f*.

The head valve *j* is also used in directing a measured charge of lubricating oil or other liquid from the measuring chamber into the can during the filling. This passage of liquid is not directly from the head valve *j* into the can but by way of a discharge valve chamber *l* (Figs. 11 and 14) which is associated with each can filling head.

A can valve *m* is located in each of the discharge valve chambers *l* and cooperates with the corresponding head valve *j* associated with that particular discharge valve chamber to insure a more accurate and uniform filling of the can. Each discharge valve chamber *l* is also equipped with a non-drip suction device illustrated in detail in Figs. 11 and 13 and designated broadly by the letter *n*.

By means of this feature the discharge passage of each filling head, after the can has been filled, is subjected to the action of suction. Any tendency therefor of an adhering excess liquid to drip from the filling head is prevented with a resulting clean and clear-cut filling operation.

After a can has been filled it is swept from the stationary table *c* by a discharge device designated broadly by the letter *p* (Fig. 3).

The apparatus is carried by a main stationary frame 21 (Fig. 2) which is centrally formed as a circular projection 22 near the top of the frame. The stationary platform or table *c* is carried on and bolted to the frame 21. This platform or table takes the form of a circular plate 23 which is provided with a central hub section 24. This hub fits over the frame extension 22 and is bolted to the frame. Frame extension 22 is projected upwardly as a support sleeve 25 (Figs. 2 and 3) which carries the turret member *d*, the reservoir *g* and the filling heads with their measuring chambers *h* and their valves *j* and *m*.

The sleeve 25 terminates in an enlarged cap section 26 on which the filling heads, turret member and reservoir frame parts move. The body or frame portion of the filling head units includes a central housing 27 formed with a top web 28 which rests and rotates directly on the frame sleeve cap 26. Reservoir *g* is located above

the web wall and is set off and confined in the middle of the apparatus by a cover member 29 which is bolted to the web wall.

The housing 27 is also carried on top of the 5 turret member d. This turret member is formed with a central cylindrical casing 31 which is rotatably mounted at its lower end on the extension 22 and at its top is bolted to the bottom of the housing 27. The casing 31 also surrounds 10 the support sleeve 25.

The casing 31 is formed as an integral part with spaced horizontal upper and lower turret discs 32 and 33 in which are formed the pockets for receiving and holding the cans as will be 15 fully described after first considering the feeding-in of the cans.

The can timing device e which first functions before the can a is put into the machine comprises an endless conveyor belt 41 (Figs. 1, 3, 4 20 and 6). At the machine end this belt passes over a pulley 42 which is mounted for rotation on a support shaft 43 carried in a feed-in table 44 which is a part of the table plate 23 which is supported on the frame 21 as previously described.

The cans a are carried on the upper run of the belt 41 and first pass between feed table side guides 45 (Figs. 1 and 3). At the inner end of the table the cans come between the end of a 30 horizontal lower circular guide rail 46 (seen at the right in Fig. 6) and a relatively short guide plate 47 (see also Fig. 4). Only the end of the lower circular guide rail is disposed near the table 44. This lower rail surrounds a large portion of the can's circular path through the apparatus. A horizontal upper circular guide rail 48 is spaced above the lower rail.

The two circular rails 46, 48 are practically the same size and extent, the lower rail being 40 used to guide the can near its bottom end and the upper rail being used to guide the top of the can. Further details of their supports, etc., will be given later.

The feed table end of the guide rail 46 is bolted 45 at 49 (Fig. 6) to the table 44. In a similar manner the plate 47 is bolted at 50 to the opposite side of the feed table. The cans after leaving the side guides 45 are thus held in proper line by the members 46, 47 and while still on the belt 50 41 the first can in the line moves against a curved arm 51 (Figs. 3, 4 and 6) which also constitutes a part of the can timing device e.

Arm 51 is formed on the forward end of a vertically disposed plate 52 (Fig. 6) which is 55 provided on one side with a T-slot 53. This construction permits a slidable mounting of the plate on a T-shape block section 54 formed in the guide plate 47. The arm 51 holds back the line of cans until it is time for a can to enter into 60 a pocket of the turret member d. Fig. 5 shows the retracted position of the arm. This timing of the arm is effected through the medium of certain control devices illustrated in detail in Figs. 6 and 7.

65 A boss 57 is formed as an integral part of the plate 52 and is located adjacent the bottom edge and on its inner side. A pin 58 is carried in the boss and engages within a slot 59 of a bell crank lever 60 (Figs. 6 and 7) mounted for oscillation 70 on a stud 61 carried in a horizontal web part 62 of the frame 21.

The bell crank lever 60 is also slotted at 63, this being on the other arm of the lever from that containing the slot 59. A pin 64 operates in the 75 slot 63 and is carried on one end of a slide rod 65

which is mounted for sliding movement in a block 66 carried upon and bolted to the frame web 62. The rod 65 at the end opposite to the pin 64 carries a second pin 67 on which a cam roller 68 operates.

A spring 69 is located in the block 66 and bears against a head formed on the forward end of the rod 65. This construction normally holds the cam roller 68 against the face of a peripheral cam 71 which is mounted upon and carried by 10 a vertical shaft 72. The shaft is rotated in any suitable manner in proper time with the movement of the turret member d and is journaled in bearings 73, 74 formed respectively in the frame web 62 and in a spider web frame 75 associated 15 with the discharge device p. Frame 75 is secured rigidly to the main frame being formed with a lug 76 which engages a similar lug 77 formed on the frame web 62, a bolt 78 locking these parts together.

When the turret member d comes into proper position to receive a can from the timing device e that section of the peripheral surface of the cam 71 which is presented to the roller 68, slopes inwardly or toward the center of the shaft 72 and 20 this allows the spring 69 to shift the parts just described. The arm 51 accordingly moves forward to the position shown in Figs. 1 and 3. The foremost can in the line is then just in front of an advancing pocket moving forward with the 30 rotating turret member d.

The turret member being composed of two turret discs 32, 33, provides a double can pocket which is formed by two spaced vertically aligned pocket spaces. In other words each turret pocket 35 comprises an upper pocket space 81 (Fig. 1) and a lower pocket space 82 (Fig. 3) formed in the peripheries of the upper and lower turret discs. Outward projections 83, 84 of the turret discs provide the rear walls for the pocket spaces 81, 40 82 and during a single rotation of the turret member each pair of projections moves into engagement with a can, when one is positioned against the arm 51 of the feed-in conveyor devices, and then slides the can over the support plate 23 45 and around a circular path of travel. Fig. 2 shows a can in its pocket and supported by the plate 23.

A tubular shaft 85 is disposed centrally of the frame sleeve 25 and is utilized to move the filling heads, the turret member and parts associated therewith. It is provided at its upper end with a flange 86 which rests upon and is bolted to the web 28 of the filling head housing 27. The tubular shaft 85 extends down through the frame section 22 and into a gear chamber 88 enclosed within the frame 21. A gear 89 may be secured on the lower end of the shaft. Such construction exemplifies broadly the idea of actuating means for rotating the shaft and through it the other movable parts of the apparatus.

At its extreme lower end, the shaft 85 passes through a bearing 91 formed in the upper end of a liquid tight housing 92 which is an integral part of the apparatus frame 21. A stuffing box 65 93 within the bearing and surrounding the shaft, effects a liquid tight movable joint at this place. Oil or other liquid which is being run in the apparatus for filling into the cans may be introduced into the chamber enclosed by the housing 70 92 as by way of a liquid supply pipe 94. The chamber is kept completely filled while the apparatus is running and the oil passes up through the shaft 85 and completely fills the reservoir g.

Again referring to feeding a can into a turret 75

pocket, it will be understood that the foremost can in the line, when presented by the arm 51, to the rotating turret, is picked up by the pocket walls 83, 84 and is moved away from its position in the line on the conveyor belt 41 (see Fig. 5). As soon as this can has cleared the remaining line of cans, the cam 71 draws the arm 51 back against the first can in the line of cans on the conveyor belt. This action is so timed that the can is caught before it has a chance to move very far and thus denting of the body wall is avoided. The arm 51 then immediately is returned to its forward holding position placing its held can in position for the next turret pocket. This action is continued and successive cans are rapidly introduced into the machine.

When a can is fully seated in the turret pocket it is well supported in the rear and adjacent top and bottom by the spaced turret members 32, 33 (as best illustrated in Fig. 2) and at the same time an intermediate engagement of the body wall is made in front by a holding finger 101 (Figs. 2, 3 and 4). The holding finger is mounted on a vertical rock shaft 102 journaled in a boss 103 extending above and below the horizontal wall part of the turret disc 33.

Movement of the finger 101 into its can engaging position is effected by means of a stationary cam and for this purpose an arm 104 is secured to the lower end of the shaft 102. This arm carries a cam roller 106 (Fig. 3) which is moved in a two-walled cam track or cam groove 108 formed in the upper face of the hub 24. The shape of this cam track is such as to provide the proper movement to bring the finger 101 into its holding position and then to hold the can throughout the filling operation.

The turret propelled can after leaving the arm 51 actuates the can trip device *f*. Reference should now be had to Figs. 1, 2, 3, 4 and 5 which illustrate the various parts of this can trip device. A can trip finger 111 is the part engaged by the advancing can and this finger is pinned to the top of a vertical shaft 112 which has oscillating movement within a bearing 113 formed in the plate 23.

An arm 114 is also pinned to the shaft 112 below the bearing 113 and this arm is pivotally connected to a link 115, the opposite end of which is pivotally connected to an arm 116 which is pinned to the lower end of a vertically extending rod 117 (Fig. 2).

The shaft 117 together with other parts of the can trip device *f* are carried in and on frame sections which are supported by the main machine frame 21. As disclosed in Fig. 2 a bracket 121 is extended outwardly from one side of the main frame and supports an intermediate frame part 122. The latter frame is tied to the bracket 121 by a vertically disposed locking rod 123 (see also Fig. 3) and is formed with a U section 124. The rock shaft 117 is mounted in lower and upper bearings 125, 126 both bearings being formed in the intermediate frame 122.

Frame 122 (Fig. 2) also provides a support for both bottom and top circular guide rails 46, 48 the former being bolted to a lug 127, the latter to a similar lug 128 formed in the frame section 124. As has already been suggested the rails 46, 48 guide the can in its travels with the turret by cooperating with turret parts 83, 84 and with the holding finger 101. These rails are also supported at two other places, in a second intermediate frame 131 (Fig. 1) and in a third intermediate

frame 132 (Figs. 1 and 6). These are carried by the main frame 21.

Frame 131 may be carried on a bracket similar in construction to the bracket 121. Frame 132 (Figs. 1 and 6) is carried on a boss 133 projecting upwardly from the web section 62 of the main frame and is held in supported position by a locking rod 134. Projecting shelves 135, 136 extend inwardly from the frame 132 and support the circular guide rails 46, 48 this constituting the exit end support of the rails.

The rock shaft 117 (Fig. 2) of the can trip device *f* adjacent its top end carries an arm 145 which is adapted to engage the lower end (see also Fig. 8) of a latch finger 147 which is pivoted on a pin 148 carried in the bearing 126. The latch finger 147 constitutes an actuating member for the valve actuating instrumentalities *k* which will be hereinafter explained. When the latch finger 147 is actuated by a can engaging the trip finger 111 as has just been explained the finger is in the position illustrated in Fig. 2 where the lower or tail part of the finger is located in position for actuating the head valve *j*.

Latch finger 147 is normally in the position illustrated by the dotted lines in Fig. 2 and thus there will be no movement of the latch finger unless and until a can is pocketed in the turret and moves past the trip finger 111 preparatory to the filling operation. In order to normally hold this position of the latch finger there is provided a spring barrel 151 which is forced against the upper part of the latch finger by a spring 152, spring and barrel being confined within an opening formed in a boss 153 which is an integral part of the intermediate frame section 124.

An adjustable compression of the spring is effected by an adjusting screw 154 which is threadedly engaged in the opening formed in the boss 153. A lock nut 155 may be utilized to hold the screw 154 in locked position. When a can seated in the turret engages the trip finger 111 the latch finger 147 is set into the full line position of Fig. 2 and as soon as the filling head unit associated with the tripping can moves its head valve *j* adjacent, the valve actuating instrumentalities *k* start the discharge of liquid from the measuring chamber *h* as will now be described.

Each measuring chamber *h* is cylindrical in shape and is contained within a chamber housing 161 (Figs. 1, 2, 8 and 11) which is formed as an integral part of the filling head housing 27. The drawings illustrate six of these chamber housings which are radially disposed with reference to the central shaft 85. The outer end of each chamber housing extends over and beyond the outer edge of the track 23. A housing or cylinder head 162 is bolted onto the outer end of each housing and closes off the end thereof.

The outer end wall of each measuring chamber proper is formed by an adjustable wall part 163 which is a piston fit having a sliding liquid-tight engagement with the walls of the chamber. This adjustable wall part is adapted to be moved relative to the cylinder head 162 and such movement alters the longitudinal dimension of the measuring chamber. This adjustment makes it possible to provide the desired cubical capacity for the measuring chamber and by the same token this controls the measured charge of liquid which is to be filled into the cans.

An adjusting bolt 164 is formed with an inner head 165 which has loose connection in the wall element 163. Bolt 164 extends outwardly through a boss 166 formed in the cylinder head 75

162. The bolt 164 is threaded in the cylinder head boss and its outer end is provided with a flat wrench part by means of which the bolt may be turned.

5 Rotation of the bolt slides the wall element 163 in and out to locate it in its desired adjusted position after which the bolt is locked against further rotation by a lock nut 169 threadedly mounted thereon. A dowel pin 171 prevents 10 turning of the wall part within the cylinder, this dowel pin extending inwardly from the cylinder head where it has loose sliding movement in a bore formed in the wall part.

Each measuring chamber *h* (Fig. 2) contains 15 a measuring piston 174 which is adapted to be moved alternately from one end of the chamber to the other. When moved in either direction a measured charge of liquid is filled into a can. A movement in a single direction takes place in 20 a single revolution of the turret member *d* and each movement comprises a full cycle of filling. For the next can to be filled from that particular filling head, the piston moves in the opposite direction within the measuring chamber and this 25 constitutes a subsequent filling cycle.

The actual measuring capacity of that part 30 of the measuring chamber which is used for each of the two cans filled in the two piston movements is the same whether the measured charge of liquid is forced out of the measuring chamber by the inward or by the outward piston travel. When the piston is at the extreme inner 35 end of its travel it will be against the inner wall of the filling head housing and the actual effective measuring space of the chamber will then be between the outer face of the piston and the inner face of the wall part 163. When the piston has moved to the outer end of its travel and is against the wall 163 the actual effective 40 measuring space will be that confined between the inner face of the piston and the inner housing wall of the chamber.

By means of this arrangement it is not only 45 possible but most economical to have the measuring chamber *h* completely filled with oil or other liquid being used in the machine and the volume of oil at all times present on both sides of the piston will equal in amount the capacity of the entire chamber confined between the inner face of 50 the wall part 163 and the inner wall of the housing less the volume which is displaced by the piston. To change such gross capacity the wall part 163 is moved as has already been fully explained.

55 The measuring piston 174 comprises two half pistons 175, 176 which are tied together by screws 177. Annular washers 178 of the pump leather type are formed with a right angled cross section and the inwardly projecting flange part of each 60 washed is clamped between the piston members.

From the brief explanation just made of the movement of the piston 174 to effect a measuring operation it will be evident that during such a 65 movement the oil or other liquid is being discharged from one end of the chamber while oil is being forced into the opposite side. This arrangement requires numerous passageways or other openings in the filling head so that the oil 70 will be delivered from the reservoir *g* as it is required by each individual filling head and in order to at all times keep the chamber filled regardless of the stage of filling. The head valve *j* is associated with such passageways and controls 75 the passage of the liquid into and out of the meas-

uring chamber and this will now be considered in detail.

A head valve block 185 (Figs. 2, 8 and 16) is mounted below each of the cylinder housings 161 and is securely bolted in position as by screws 5 186. This valve block is extended into a lower body part 187 through which a tapered valve seat opening 188 passes. The active or movable part of each head valve *j* is formed as a conical member 191 which is seated in its valve seat opening 10 188.

The valve member 191 has four positions, two closed positions at which time all of the valve parts are blocked and two open positions each of which is associated with the filling of a can. In 15 one open position communication is provided by way of ports in the valve between the reservoir *g* and the inner end of the measuring chamber. When in this open position communication is also made between the opposite or outer end of the 20 measuring chamber by way of ports in the valve to the discharge valve chamber *l*. The valve member 191 makes only a half turn during one filling cycle so that it passes through one open and one closed stage at such a time this being for 25 one can.

In the second open position the valve connects certain passages leading between the reservoir and the outer end of the measuring chamber, this being at the next or at a later revolution for 30 a succeeding can and in such a second position liquid is caused to flow from the inner end of the measuring chamber by way of ports in the valve to the discharge valve chamber *l*.

Each chamber housing 161 is formed on one 35 side with a short inclined boss 195 (Figs. 1 and 11) which provides increased stock through which an inclined passageway 196 leads down from the reservoir *g*. The lower end of the passageway is in direct communication with a vertically disposed leg 197 (see also Fig. 17) of a right angled passageway formed in the head valve block 185 there being also a connecting horizontal section or leg 198 which extends to the valve seat opening 188. 45

The passageways 196, 197, 198 provide for delivery of the liquid from the reservoir *g* into the inner end of the measuring chamber *h* when the valve member 191 is in its first open position as in Figs. 2, 17, 18 and 19. The valve member *j* of 50 each filling head unit is provided with a right angle port 201 arranged in the smaller end of its tapered section or at the right (Fig. 2). With this first open setting of the valve, the valve port connects the leg 198 with a vertical leg 202 and 55 a connecting horizontal leg 203 of a passageway formed in the valve block 185 just below the measuring chamber.

The inner end of the passageway section 203 terminates adjacent a port 204 which is cut in 60 the lower wall of the measuring chamber housing and which is in connecting alignment with a tapered opening 205 formed in the inner end wall of the measuring chamber. With the valve part 191 so positioned, liquid will flow by reason of the 65 pressure maintained on the body of liquid, through the passageways 196, 197, 198 through the valve port 201 thence by way of the passages 202, 203 and ports 204, 205 into the inner end of the measuring chamber *h*. 70

The pressure exerted by the liquid within the reservoir moves the piston 174 along the chamber as has already been suggested. When the piston moves toward the left (Fig. 2) liquid is discharged from the outer or left end of the measuring cham- 75

ber. The inner face of the adjustable wall part 163 is formed with a tapered opening 206 which, like the opposite opening 205, provides for passage of liquid back of the plane of the face of the wall part. At its lower end the opening 206 communicates with a port 207 which is cut in the lower wall of the measuring chamber housing. Port 207 is at the end of a horizontal leg 208 of a right angled passageway formed in the block 185. 5 A vertical leg 209 of this passageway leads to the valve seat 188.

The valve 191 in its first open position now being considered is located with a longitudinal port sector 211 adjacent the top, one end of this 15 port being in communication with the lower end of the vertical passageway 209. The opposite end of the port sector (see also Fig. 18) communicates with a vertical leg 212 of a passageway which also extends as a horizontal section 213, 20 these being formed in the valve block 185.

The horizontal leg 213 is at all times in communication with a port 214 which is formed in the side wall of a can valve nozzle housing 215 (Figs. 1, 8, 11 and 18). This nozzle housing is tubular 25 in shape and is mounted alongside of each valve chamber housing 161 being securely held in position by a holding plate 216 bolted to the housing as at 217.

As the piston 174 moves toward the left (Fig. 30 2) the measured charge of liquid contained within the measuring chamber space, between the forward face of the piston and the end wall member 163, is forced out through the ports 206, 207, passageways 208, 209, valve port 211 and 35 passageways 212, 213 and thence into the discharge valve chamber 1. From the chamber 1 the liquid discharges into the can. This further action, being under the control of the can valve *m* which has not yet been described in detail, will 40 be explained hereinafter.

While the measured charge of liquid is passing out of the measuring chamber, the propelling liquid entering behind and acting upon the advancing piston 174 is maintaining the chamber filled 45 with liquid. By the time the piston reaches the end of its stroke (this being at the extreme left when viewed as in Fig. 2), the newly filled space between the inner end wall of the chamber and the piston becomes the new effective measuring 50 chamber and the liquid therein is of an exact predetermined quantity.

In the next filling operation of the measuring chamber *h*, therefore, the flow of liquid into and out of the cylinder will be reversed, this reversal 55 of conditions being brought about by a change in position of the valve part 191. Upon the piston 174 reaching this left hand position at the end of its stroke, the valve part 191 is immediately moved through 90° (counter-clockwise as viewed in Figs. 60 17, 18, 19 and 20) bringing it into its first shut position (Fig. 20). In such closed position the passageways 212, 213 are blocked off and no further liquid enters into the discharge valve chamber 1. It is at the same time that the can 65 valve *m* closes so therefore the discharge chamber remains filled with liquid ready for immediate flow into a subsequent can. While so closed the filled can is discharged.

The valve member 191 when moved into its 70 second open position is turned through an additional 90°. This takes place, however, in another revolution of the turret member and with another can and will next be considered. On the side of each housing 161, that is opposite to the 75 short inclined boss 195, there is provided a long

inclined boss 221 (Fig. 1) which provides increased stock through which an inclined passageway 222 leads from the reservoir *g*. The lower end of this inclined passageway is in direct communication with a vertically disposed leg 223 5 (see also Fig. 19) of a right angled passageway formed in the head valve block 185 this passageway also having a horizontal section or leg 224 which extends into the valve seat opening 188.

The valve member 191 is provided with a right 10 angle port 225 (Figs. 2 and 19) this port being formed in the larger end of the tapered valve section. With the valve in its second open position, now being considered, the valve port 225 connects the end of the passageway 224 with the 15 vertical passageway leg 209 thus opening the way through the passageway leg 208 and ports 207, 206 and with the outer end of the measuring chamber. The reservoir liquid under pressure 20 now effective by way of these passageways and ports presses against the outer face of the piston 174 and causes it to move from its extreme outer position within the measuring chamber toward the right (as viewed in Fig. 2).

At the same time the measured charge of liquid 25 contained within the effective measuring space of the chamber and to the right of the piston 174, is discharged out through the ports 205, 204 and passageways 203, 202 into the passageways 212 and 213 by way of a second valve port sector 30 226 by means of which the liquid is caused to flow into the discharge chamber 1 along the same course as previously described for the filling of a preceding can.

The complete discharge of the measured liquid 35 from within the measuring chamber is followed by the next movement of the valve part 191, through a third quadrant bringing it into its second shut position, this being the position illustrated in Fig. 21. It will be observed that the 40 passageway 198 and also the passageway 202 are again blocked off and no further flow of liquid takes place while the valve remains in this position.

The valve actuating instrumentalities *k* which 45 operate to turn the head valve member 191 through its various positions will now be considered and reference should be had to Figs. 2, 8 and 16. Each head valve member 191 is slotted at 245 this being at the large end of the valve 50 member and outside of the valve seat. This slot provides operating connection for the valve actuating instrumentalities *k*.

These instrumentalities comprise a horizontal 55 shaft 251 which is rotatably mounted in axial alignment with the valve member 191 and in a support block 252, the latter being bolted at 253 to the head valve block 185. The shaft 251 is formed with a flat head 255 which extends beyond the inner end of the block 252 and projects 60 into the slot 245 of the valve member 191. This provides a flexible connection so that turning of the shaft will effect a corresponding rotation of the head valve.

Liquid-tight contact is formed between the 65 valve and the valve seat by reason of the tapered form of the valve and seat and the valve is yieldingly held in its position under the action of a spring 256 which is located in a central bore formed in the inner end of the shaft 251. A 70 spring barrel 257 has sliding contact within this bore and a rounded head of the barrel presses against the end of the head valve under the expanding action of the spring.

Reference has already been made to finger 75

147 which has been rocked into valve actuating position (Fig. 2) by the can trip device *f*. It is this finger which causes turning of the shaft 251 to establish the two open positions of the valve member 191. Shaft 251 carries a four fingered starwheel 261 (Figs. 2, 8, 9 and 10) which is mounted on the outer end of the shaft and is held in place by washer and screw elements 262.

5 The starwheel 261 is formed with two oppositely disposed outer fingers 263, 264 and similarly shaped inner fingers 265, 266. When a can is first brought into the apparatus and located for filling in one of the filling head units and within the turret member *d*, the starwheel 261 associated therewith is first engaged by the finger 147 and is moved through its first 90°. This engagement is between the finger 147 and the starwheel finger 263 when considering the setting illustrated by Fig. 8 which shows the position of the parts after the first valve movement. The head valve 191 which is in closed position when the can is received is thus moved into its first open position for the discharge of liquid from the measuring chamber and for the filling 10 of this liquid into the can.

15 In each of the four positions of the shaft 251, it and the starwheel 261 are locked against inadvertent movement and until it is the proper time for the next valve shift. For this purpose 20 a locking plate 267 is mounted on the shaft 251 and is keyed thereto, this plate being positioned just inside of the starwheel 261. Locking plate 267 is formed with four straight sides and the corners connecting adjacent sides are rounded as 25 illustrated in the drawings.

25 A circular rail 268 is utilized to hold the locking plate in each of its four positions, a straight side of the plate at all times moving along the bottom edge of the rail. This rail is preferably 30 formed with a right angle cross section (Fig. 2) and is supported in a fixed position on the frame part 122 to which it is bolted as at 269 (Figs. 1 and 2) and on the intermediate frames 131, 132 to which it is bolted as at 270 and 271 (Fig. 1). 35 Adjacent the actuating finger 147 the bottom edge of the rail 268 is relieved in a notch 272 (Fig. 8) and this permits the corner of the locking plate 267 to swing up and pass within the notch during the rotation of the shaft as effected 40 by engagement of the finger 263 with the finger 147. As soon as the shaft, valve and starwheel, 45 however, has been moved the full 90° they have been carried beyond the notch 272 whereupon the newly presented straight side of the locking plate 50 267 slides along the bottom edge of the rail 268 thus holding the movable parts in their actuated position.

55 Turning of the shaft 251 also effects the opening and closing of the can valve *m* located in the associated discharge valve chamber *l*. For this purpose each shaft 251 carries a cam block 275 (Figs. 2, 8 and 11) which is keyed to the shaft on its projecting inner end. This cam block is formed with two projecting surfaces 276 each of 60 which is adapted at certain times to engage instrumentalities associated with the actuation of the can valve *m*.

65 The can valve *m* comprises a valve head 281 (Figs. 11 and 14) which is threadedly mounted 70 on the lower end of a valve stem 282, the valve stem being disposed centrally of the discharge valve chamber *l*. The valve stem has sliding movement in a bearing 283 formed in the valve nozzle housing 215, this bearing being located at 75 the top of the discharge valve chamber *l* and in a

bearing 284 formed in an inner casing 285 located in the valve housing 215 and restricting the size of the discharge valve chamber. A stuffing box 286 is provided for bearing 283 so that liquid within the chamber will not escape around the valve stem. The upper end of the valve stem 282 is also slidably retained in an additional bearing provided by a threaded nut member 287 threadedly secured in the top of the valve nozzle housing 215.

10 The valve head 281 and valve stem 282 are normally held in lowered or closed position (Fig. 14) on a valve seat 288 which is formed in a nozzle cap 289 threadedly secured to the lower end of the valve housing 215. This holding of the valve head in seated position is effected by a spring 290 which surrounds the valve stem 282 and is interposed between the lower end of the nut 287 and an enlarged middle section of the valve stem. To fill a can it is necessary to raise the valve stem 20 282 and its valve 281 into the position illustrated in Fig. 11 and this is effected by the cam 275 in the following manner.

25 The valve stem 282 at its upper end passes through a slot 291 formed in a slide 292 (Figs. 8 and 11) which is mounted alongside of the valve nozzle housing and is retained in slideways formed by side plates or gibs 293 secured to the housing 215. The upper end of the valve stem 282 is threaded and lock nuts 294 provide a stop 30 which is engaged when the slide 292 is raised.

30 The slide 292 carries a pin 295 which provides a pivoted connection for the upper end of a strap 296, the lower end being pivotally connected at 35 297 with one arm of a bell crank lever 298 which is mounted for oscillation on a stud 299 carried in the valve housing 215. The opposite arm of the bell crank lever carries a cam roller 301 which rides against the periphery of the cam 275.

35 When the shaft 251 is first actuated and its 40 star-wheel 261 is brought into the first valve open position shown in Fig. 8, one of the cam projections 276 forces against the roller 301 and rocks the bell crank lever 298. This lifts the strap 296 and the slide 292 which in turn raises 45 the valve stem 282 and the valve head 281 from its seat 288. This forms an opening in the bottom of the discharge chamber *l* as shown in Fig. 11 and the liquid discharges into the can, this lifting of the cam valve *m* being simultaneous 50 with the opening of the head valve 191 the liquid thus flowing from the measuring chamber by way of the discharge chamber *l*.

55 After filling, the head valve 191 is moved to its off position and the valve 281 is closed this 60 being the second 90° of movement of the star-wheel 261 the turning of the starwheel being illustrated in Fig. 9. A stationary block 305 (see also Fig. 1) is bolted to the under side of the circular rail 268 and the filling head unit being 65 considered now passes this position. The finger 265 of the starwheel 261 strikes against the block 305 (Fig. 9) and the starwheel is thus moved the 90° of its rotation.

65 At the same time the corner of the locking 70 plate 267 passes adjacent and moves through a slot 306 formed in the bottom edge of the circular rail the locking function of the plate 267 then being nullified. Also at the same time the projection 276 of the cam 275 moves out of engagement with the roller 301 whereupon the spring 290 returns the valve 281 into its closed position. As soon as this closing of valves takes place the non-drip suction device *n* is brought into play and this will next be described.

It should be evident that the third and fourth quadrant movements of the valve are brought about in the same manner and on a subsequent revolution of the turret. For the second open position of the valve, the 90° of movement is brought about by engagement of the finger 147 and the starwheel finger 264 and valve *m* is actuated by the other cam projection 276 engaging with the roller 301. The closed valve position is effected by engagement between the block 305 and the starwheel finger 266.

The valve head 281 (Figs. 14 and 15) is slotted along one diameter as at 311 and the valve stem 282 is hollow in its lower half in a central bore 312, the lower end of which communicates with the slot 311 of the valve head. A drip shield 313 is threadedly engaged in the lower end of the valve head 281 and this shield is apertured at 314 where it joins with the valve head slot 311 and the aperture 312 of the valve stem. The drip shield 313 is conical in form and when screwed into position within the valve head there is provided an annular clearance space 315 which communicates at its lower end with the outside 25 of the valve head and at the inside with the slot 311 formed therein.

The valve nozzle housing 215 above the bearing 283 is open along its central axis where it surrounds the valve stem and this provides a suction chamber 316 (Figs. 11 and 14). A transverse port 317 is cut through the valve stem 282 from both sides and this port intercepts the central aperture 312 and opens out into this suction chamber. A port 318 extends through the nozzle housing and its inner end opens into the suction chamber. This port joins with a vertically disposed port 319 also formed in the housing. The port 319 at its upper end communicates with the inside of a curved pipe 321, the upper end of which is threadedly engaged in an upper head ring 322 formed in the cover member 29. There is only one head ring but there are as many pipes 321 as there are filling heads.

A suction head 323 (Figs. 8, 11, 12 and 13) is mounted on the head ring 322 and is secured in place by screws 324, this part, therefore, rotating at all times with the filling heads, the reservoir and other associated rotatable parts of the apparatus. Each pipe 321 at its upper end opens into a port 325 formed in the head ring 322 and is in constant communication with the lower end of a vertical port 326 cut in the suction head.

It is the associated port 326 of each filling head that is selectively opened up to a vacuum condition at the time that the can valve *m* shuts off the flow of liquid into the can being filled. The resulting non-drip function thereupon operates and any extraneous liquid is removed from the filling nozzle.

The suction head 323 is provided with a central opening 331 and a stationary tubular member 332 extends into and through the opening 331. The lower end of the tubular member has a flange 333 which engages under the bottom of the suction head 323, a stuffing box 334 being provided to prevent leakage of air through the joint within the rotating seat of the suction head. The tubular member central opening as at 335 connects above with a pipe 336 which leads from any suitable source of vacuum as from a vacuum pump or tank not shown.

The head ring 322 of the reservoir cover member 29 is provided with a drip chamber 337 and the tubular member 332 opens this chamber at all times to direct communication with the source

of vacuum from the pipe 336. Any extraneous liquid which may adhere to the valve head 281 or nozzle parts is drawn up through the space 315 and into the slot 311 of the valve and thence by way of the bore 312, the ports 317, chamber 316, ports 318, 319 and pipes 321 through the openings 325, 326 and thence into the suction chamber 331 where it drops down to the bottom of the chamber. At stated intervals this suction chamber may be blown out or otherwise emptied.

The selective connecting of a port 326 with the suction chamber is effected by a suction valve device which includes the rotating suction head 323 and a stationary valve plate 341 (Figs. 11, 12 and 13). The valve plate 341 is mounted on the tubular member 332 and is backed up by a disc 342 and is pressed down against the upper surface of the suction head 323 in an airtight joint, lock nuts 343 being threadedly secured to the upper end of the tubular member 332 for this purpose.

When communication is made between the upper end of a port 326 and the suction chamber 331, the port is moved into register with an arcuate slot 345 formed in the stationary plate 341 as shown to the left in Fig. 12. The plate 341 is also formed with an inner circular channel 346 which communicates at all times by means of connecting passage 347 with the arcuate slot 345. The circular channel 346 is at all times in communication with the upper ends of tapered ports 348 (Figs. 12 and 13) formed in the suction head 323, the lower end of each port opening out into the top of the chamber 331.

By means of this construction suction is applied at all times to the central channel 346 and in the arcuate slot of the valve plate 341 by way of the ports 348, suction chamber 331 and tubular member 332, and as soon as a port 326 is brought into communication with the arcuate slot 345 the air is withdrawn from the various ports and other passages together with any entrained liquid which may be brought up from the valve head.

The filled can is removed from the apparatus by the discharge device *p* which is shown in some detail in Figs. 3 and 6. The can still retained in the turret pocket is swept from the stationary support table 23 and is brought onto the surface of a constantly revolving discharge disc 351 which is carried on the upper end of the vertical shaft 72. This transfer from table to disc is shown to the upper left of Fig. 3. Immediately following this the finger 101 is retracted as the can continues around its circular path under action of the turret.

During the transfer to the circular disc 351, the can is kept in its turret pocket by the circular guide rails 46, 48. Both rails terminate substantially on a line joining the centers of the shaft 72 and the tubular member 85, the terminal ends of the respective rails 46, 48 being designated by numeral 352 (Figs. 3 and 6) and the numeral 353 (Figs. 1 and 6).

About the time the finger 101 has moved away from in front of the can, the can has reached the terminal ends 352, 353 of the guide rails and just previous to this the can moves into lower and upper circular guide rails 354, 355 (Figs. 1, 3 and 6) which are disposed around the outer edge of the disc 351. Rail 354 is mounted on the spider web frame 75. Rail 355 is carried on spacer rods 356 which are passed through the rail 354 and are threaded into the web frame 75.

These circular rails 354, 355 wedge the can out from its turret pocket and spaced discharge fingers 357 carried on a hub 358 thereupon engage back of the can and together with the disc 351 carry it around a circular path of travel as guided by the rails 354, 355 and remove the can from the machine. The hub is mounted on the upper end of the shaft 72 and turns with it.

It is thought that the invention and many of its attendant advantages will be understood from the foregoing description, and it will be apparent that various changes may be made in the form, construction and arrangement of the parts without departing from the spirit and scope 15 of the invention or sacrificing all of its material advantages, the form hereinbefore described being merely a preferred embodiment thereof.

We claim:

1. In a machine for filling liquids into cans, the combination of a filling head having a measuring chamber and also having a discharge chamber, a reservoir for containing a filling liquid, means for supplying said reservoir with liquid, a discharge piston located in said measuring chamber, the filling liquid moving said discharge piston within said chamber to force out a measured charge of liquid into and through said discharge chamber, a head valve carried in said filling head for opening and closing communication between said reservoir and said measuring chamber and between the latter and said discharge chamber, a can valve located in said discharge chamber for cutting off communication between the chamber and a can positioned for filling, and a valve actuating means for simultaneously moving said can and head valves to effect flow of the filling liquid into said measuring chamber while liquid is passing from said chamber into the positioned can.
2. In a machine for filling liquids into cans, the combination of a filling head having a measuring chamber, means for positioning a can beneath said measuring chamber, means for supplying said chamber with liquid under pressure, a discharge piston located in said measuring chamber, a head valve mounted in said filling head adjacent said chamber for opening communication at one end of said measuring chamber with said positioned can to be filled and for opening communication with the other end of the chamber with said liquid supplying means, a can valve also mounted in said filling head and interposed between the can to be filled and the said head valve, the filling liquid moving said discharge piston to force out a measured charge of liquid from said measuring chamber, control
- means for operating said head and said can valves in cooperation with said piston moving means to insure delivery of a predetermined measured charge of liquid into said can, and a no-can-no-fill trip device for setting said valve control means for operation only in the event that said can is properly positioned for filling.
3. In a machine for filling liquids into cans, the combination of a centrally disposed liquid reservoir, a rotatable filling head having a measuring chamber extending radially outwardly from said reservoir, means for bodily rotating said filling head in a circular path of travel, means for supplying said chamber with liquid under pressure, a discharge piston located in said measuring chamber, a head valve mounted in said filling head adjacent said chamber for opening communication between one end of said measuring chamber and a can to be filled and for opening communication between the other end of the chamber and a supply of filling liquid, a can valve also mounted in said filling head and interposed between the can to be filled and the said head valve for controlling the passage of the liquid into the can, the liquid to be filled moving said discharge piston to force out a measured charge of liquid from said measuring chamber, and control means for operating said head and can valves to effect delivery of a predetermined measured charge of liquid into said can.
4. In a machine for filling liquids into cans, the combination of a centrally disposed reservoir, a filling head having a measuring chamber extending radially outwardly from said reservoir, means for supplying to said chamber liquid to be filled, devices for feeding a can to be filled into filling position adjacent said filling head, a discharge piston located in said measuring chamber, valve means in said filling head interposed between said positioned can and said measuring chamber for opening communication between one end of said measuring chamber and said positioned can, said discharge piston being adapted to be moved radially of said reservoir by the pressure of the liquid to be filled toward that end of said measuring chamber which is in communication with said can to force out a preceding measured charge of liquid into said can, and air suction means arranged within the parts which contain the filling liquid or material and acting to withdraw extraneous drips of the latter into the filling devices.

CLINTON KRAUS. 55
